UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

VOTING-MACHINE.

1,105,598.

Specification of Letters Patent.

Patented Aug. 4, 1914.

Application filed February 13, 1911. Serial No. 608,383.

To all whom it may concern:

Be it known that I, CHARLES C. ABBOTT, a citizen of the United States, residing at Pittsfield, county of Berkshire, State of 5 Massachusetts, have invented an Improvement in Voting-Machines, of which the following is a specification.

This invention relates to the portion of the mechanism of a voting machine which has to 10 do with the casting of the votes, and to certain parts connecting this portion of the mechanism with the counting mechanism and with the paper feed mechanism used in independent voting, and for convenience is 15 herein shown as embodied in a machine of the general type shown and described in Letters Patent No. 914,006, granted to me March 2, 1909.

The general object of the invention is to 20 provide voting mechanism that will render it easy for the voter to vote for the candidates of his choice whether in one or in a plurality of party lines, will protect the voter against knowledge by others as to how he has voted, 25 and will render it impossible for the voter to vote fraudulently.

One of the objects of the invention is to improve, simplify, and make more reliable and convenient of operation certain parts 30 of the mechanism shown and described in my prior application for Letters Patent, filed July 28, 1909, Serial No. 509,991.

Another object of the invention is to provide means whereby the counting mechanism 35 may be reset after the entire vote has been cast and recorded.

A further object of the invention is to adapt the machine for use in primary voting. In carrying out this portion of my invention I have provided means for locking 40 all of the party levers against operation by the voter and means for locking all of the lines of individual voting members except those occupied by the candidates of the 45 party for whom the voter is entitled to vote, said last named voting members being unlocked and in a condition to be operated whether said members occupy one or a plurality of lines. I have further made provision 50 whereby the locking means for the lines of individual voting members may be controlled or adjusted to unlock the voting

members in the line or lines occupied by any desired party, the lines occupied by all other parties being locked.

55

With the above and other objects in view, I have devised the novel mechanism which I will now describe, referring to the accompanying drawings forming a part of this specification and using reference characters 60 to indicate the several parts.

Figure 1 is an elevation partly broken away showing the voting mechanism assembled, the parts being in the normal position, that is, before any of the mechanisms of the 65 machine have been operated; Fig. 1^a is an elevation of the entire machine looking from the rear or voting face thereof. Fig. 2 is a detail elevation, as viewed from the right, Fig. 1, of the means for locking the resetting lever when an independent shutter is 70 opened, the casing parts being shown in section; Fig. 3 is a detail elevation on an enlarged scale of one end of one of the party lines showing the corresponding party lever 75 in section; Fig. 3^a is a detail plan view of certain parts shown in Fig. 3. Fig. 4 is a view similar to Fig. 3 partly broken away of the lower party line and showing an interlocking member and the mechanism 80 connecting the releasing and restricting mechanisms; Fig. 5 is a detail plan view of one of the interlocking members and the supporting channel therefor; Fig. 6 is a plan view, partly in section, of the parts shown 85 in Fig. 3; Fig. 7 is a side elevation of the resetting shaft and parts associated therewith; Fig. 8 is a front elevation of the parts shown in Fig. 7; Fig. 9 is a detail perspective view of one of the channels for supporting the interlocking members; Fig. 10 is a front elevation, partly broken away, of 90 the main operating shaft and bar, the shafts for operating the counter grids of the counting mechanism, the paper feed shaft of the 95 independent voting mechanism, and the shaft for setting the counters; Fig. 11 is an elevation, partly broken away, one of the counter grid operating shafts shown in Fig. 10, the main operating bar and the paper 100 feed and counter setting shafts being shown in section; Fig. 12 is a plan view of the counter setting shaft shown in Fig. 10, the counter grid operating shafts being shown

in section; Fig. 13 is a detail view of the connections between the main operating bar and one of the counter grid operating shafts; Figs. 14 and 15 are detail sections taken on the lines 14—14 and 15—15, respectively, Fig. 13; Fig. 16 is a detail elevation, on an enlarged scale and partly broken away, of the connections between one of the counter grid operating shafts and the paper feed shaft; Fig. 16^a is a central vertical section of parts shown in Fig. 16. Fig. 17 is a detail plan view, partly broken away, of the parts shown in Fig. 16; Figs. 18 and 19 are sections taken on the lines 18—18 and 19—19, respectively, Fig. 16; Fig. 20 is a front elevation, partly in vertical section, of the key bar and bolts for locking the party lines for primary voting; Fig. 21 is a plan view with the framework in section of one of the primary locking bolts, the key bar, and the means for operating the same, shown in Fig. 20; Fig. 22 is an elevation with the framework in section of the parts shown in Fig. 21 as viewed from the left in Fig. 20; Fig. 23 is an enlarged detail of certain parts shown in Fig. 21; Fig. 24 is a detail elevation, viewed from the left in Fig. 21, of the latch for locking the key bar operating shaft in position during primary voting; Fig. 25 is a front elevation of the entire primary locking mechanism; Fig. 26 is a detail elevation of the key bar which carries the keys for controlling the primary locking bolts; Fig. 27 is a similar view showing the keys in position; Fig. 28 is an elevation of the same parts as viewed from the left in Fig. 27; Fig. 29 is an enlarged detail of a portion of Fig. 28 illustrating the form of the keys and the manner of securing the same in position on the key bar; Fig. 30 is an elevation of the restricting shaft and the parts associated therewith; Fig. 31 is a similar view showing some of the parts in section and in a different position; Figs. 32 and 33 are detail sectional views taken on the lines 32—32 and 33—33, respectively, Fig. 31; Fig. 34 is a detail sectional view showing the ends of the two parts of the restricting shaft and the sleeve connecting the same; Fig. 35 is a fragmentary plan view, with the casing parts in section, of a train of mechanism for locking and unlocking one of the party lines for primary voting.

The machine, as to its general organization and principles of operation, is of the type fully described in Letters Patent No. 914,006, hereinbefore referred to. Said machine comprises mechanism for casting the votes, or by which the voter indicates his choice, herein, for convenience, referred to as "voting mechanism"; mechanism for registering the vote so indicated, herein referred to as "counting mechanism"; and mechanism operated by the voter when he approaches and leaves the machine, and

herein referred to as "main operating mechanism," which coöperates with the voting mechanism to unlock, reset, and lock the same, and which actuates the counting mechanism to register the vote. These mechanisms, with the exception of certain keys and levers which are operated by the voter or the custodian, as hereinafter explained, are inclosed within an upright casing, the rear of which constitutes the voting face of the machine, and upon this are displayed the names of the candidates to be voted for. As shown in the patent above referred to the names of party candidates are placed in horizontal lines, called party lines, and the names of all candidates for the same office are placed in vertical columns, called office columns, although of course the mechanism may be arranged otherwise if preferred. Upon the voting face of the machine are also voting keys corresponding in number and arrangement to the candidate names, said keys forming parts of voting members which extend within the casing and are there provided with counter dogs. The voting members are connected in party lines by party bars to each of which is connected a party lever which may be operated to move all of the voting members in that line into voting position, as in casting a straight party vote. The counting mechanism comprises a bodily movable counter carrier or grid which carries a plurality of counters equal in number to the voting members and which are engaged and disengaged by the counter dogs when the corresponding voting members are moved into and out of voting position. The main operating mechanism includes a main operating lever, arranged at one side of the casing, and which is moved in one direction when the voter passes to the machine and in the opposite direction when he leaves it. The entrance movement of this lever operates through suitable mechanism, to unlock the voting mechanism, while the exit movement thereof operates to reset the voting mechanism and lock the same. Also, at each actuation of the main operating lever, movement is imparted to the counter grid, the entrance movement being an idle movement. At the exit movement of the counter grid all counters which have been engaged by voting members are operated to register a vote.

30 denotes the individual voting members as a whole, which I shall hereafter refer to as voting members.

31 denotes the party bars which correspond in number with the party lines of the machine, 32 (see Figs. 3 and 6) the resetting bars which correspond in number with the party bars, 33 a special resetting bar, and 34 a locking bar.

35 denotes an operating bar for the re-

70

130

setting mechanism and 36 a cam bar which is actuated by suitable connections with a main operating shaft (see Figs. 1^a and 10) previous to the casting of a vote. These 5 connections are not shown, as they form no portion of the present invention. The cam bar is provided with a plurality of vertical slots 37 and with a plurality of cam slots 38.

43 denotes the framework of the machine 10 which is formed of sheet metal forming a casing and providing the necessary supports, guides and bearings for the various bars and other parts of the machine, except as hereinafter pointed out. The party bars 15 and resetting bars are connected to the cam by means of double links 44 provided with pins 47 which pass through slots 48 in the party and resetting bars and with pins 49 carrying rollers which engage slots 38 in 20 the cam bar. Special resetting bar 33 is connected to the cam bar by means of links 190 which are pivoted to the bar 33 at 191 and carry a roller which engages one of the cam slots in the cam bar.

25 50 denotes latches which are pivoted at 51 to suitable parts of the framework and provided with pins 54 which engage vertical slots 37 in the cam bar. The forward ends of the latches are arranged to coact with 30 dogs 57 rigidly secured to the resetting bars and to lock these bars until the latches are raised.

59 denotes bell crank levers pivoted at 189 in the framework. One arm of each lever 35 is provided with a pin 60 which lies in a slot 61 in operating bar 35. The other arm of each lever is provided with means to engage the dogs 57 on the resetting bars.

66 denotes the resetting shaft which is 40 journaled in the framework and carries a resetting lever 67 (see Fig. 7) lying outside the case of the machine.

68 is a crank on shaft 66 which is connected to operating bar 35.

45 70 denotes a cam projection on bar 35 which coöperates with a lug 71 on special resetting bar 33 to retract said bar, that is, move it toward the right, when operating bar 35 is pulled down by operation of the 50 resetting lever, as will be more fully explained.

76 (see Figs. 3 and 6) denotes the party levers pivoted in the framework and extending through slots in the back plate. The inner end of each party lever, indicated specifically by 81, extends through a slot 82 in the corresponding resetting bar and through a slot in a link 84 connected to the corresponding party bar 31 by means of a stud 85 60 which passes through a slot 86 in the corresponding resetting bar. At the left end of each of the party lines, and operatively connected, by means hereafter more fully described, with the corresponding party and 65 resetting bars, is a wedge plate 88. Each

wedge plate is provided on both upper and lower sides with inclines 89 at its rear ends and inclines 90 at its forward ends. Intermediate the wedge plates 88 are other wedge plates guided for free vertical movement in 70 the framework and covered by a plate 98. A fixed wedge plate 97 forms a stop for the upper end of the wedge system. The lower wedge plate 88 engages a wedge plate 100 which, in turn, engages at its lower side a 75 wedge bar 103 supported and guided by a pin 105 riveted in the framework. The wedge system is not shown nor described in detail since, except as to certain features hereinafter referred to, it forms no portion 80 of the present invention, it being sufficient to say that when a party lever is moved to voting position the corresponding wedge plate 88 is moved to the left, the effect of which is to lock the wedge system, thereby 85 locking all of the other party levers in the non-voting position.

106 denotes a lug riveted to each party bar and having an incline 107 which is engaged by a double catch 109 pivoted at 110 (see 90 Fig. 4) to the framework. The two arms of the catch lie on opposite sides of the locking bar 34 which is provided with an aperture 111 which receives a stud 112 lying between the arms of the catch and serving as a space 95 block.

113 denotes a plate rigidly secured to each resetting bar 32 and having notches 114 adapted to be engaged by the corresponding catch to lock the resetting bar in its normal 100 position and, by reason of the engagement of this bar with the voting members, to lock said voting members.

126 denotes the restricting shaft as a whole 105 and 127 (see Fig. 30) the restricting lever which lies outside the framework of the machine on the back. In accordance with the present invention, the restricting shaft is made in two parts, as will presently be more 110 fully described.

128 denotes an arm secured to the restricting shaft.

131 denotes the releasing shaft. The functions and mode of operation of the restricting and releasing shafts will hereafter 115 be more fully explained.

143 denotes an extension of locking bar 34 at the upper end of which is a hook 146 in position to be engaged by a projection 147 on the clutch operating slide 148 which controls the paper feed mechanism (not shown).

150 denotes one of the independent shutter openings. The shutter operating mechanism is not illustrated and described in detail as specifically it forms no portion of the present invention.

The parts last referred to constitute portions of the independent voting mechanism. For the purposes of the present invention 130 this mechanism may be of any suitable form,

but for convenience of description the same may be considered as of substantially the construction and arrangement shown and described in my former Letters Patent No. 914,007, dated March 2, 1909.

The voting members 30 comprise oscillatory shafts journaled in the framework and having voting levers 151 (see Fig. 6) lying outside the machine in front.

- 10 152 (Fig. 3) denotes arms on the voting member shafts, said arms carrying pins 165 which pass through slots 193 in the resetting bars and through slots 192 in the party bars. Said party and resetting bars serve to connect the voting members in party lines as above referred to. Each voting member is also provided with a lug 155 (see Fig. 4) which is adapted to engage a cam plate of an interlocking member 156. The interlocking member used is the one illustrated and described in my former Letters Patent No. 900,905, dated October 13, 1908, and comprises cam plates 157 (see Fig. 4), side plates 158 and stud and slot connections between said plates acting to shorten the member when a cam plate is moved laterally. When a voting member is actuated, the lug 155 of said member engages a cam plate of the corresponding interlocking member, 30 forces said cam plate laterally, shortening and imparting rigidity to the member and locking all of the other cam plates so that under ordinary conditions no other voting member in that column can be operated as it will be locked in the non-voting position by the corresponding cam plate of the interlocking member. The number of interlocking members in the machine corresponds with the number of columns of names of 40 candidates.

159 denote the restricting members which lie in a horizontal line below the lower line of voting members and comprise oscillatory shafts journaled in the framework in the same manner as the voting members. Each restricting member is provided with a lug 160 which is adapted to engage a cam plate 157 of an interlocking member in the same manner as the lugs 155 of the voting members. The restricting members 159 are preferably provided with special means for locking the lower line of voting members, but such means forms no part of the present invention and is not shown. 177 (see Fig. 30) 50 denotes a second arm extending from the restricting shaft 126. A link 178 (see Fig. 4) pivoted to this arm is arranged to be operatively connected with the restricting members 159 in such a manner that when the restricting lever 127 is moved to restricting position the restricting members operatively connected therewith will be turned to bring their lugs 160 into engagement with the cam plates of the interlocking members, thereby locking all of the voting mem-

bers in the corresponding columns in non-voting position. These connections are not shown in detail as specifically they form no part of the present invention.

The mechanism thus far described is not 70 generically claimed herein as it is covered by the claims of my prior application Serial No. 509,991, aforesaid, although the present invention comprises modifications of certain parts of this mechanism as will now 75 be described.

In accordance with the present invention, the left hand end of each link 84 (as shown in Figs. 1, 3 and 4) is arranged to abut against the corresponding wedge plate 88. 80 By this arrangement movement of a party lever into voting position causes the link 84 connected therewith to force the corresponding wedge plate 88 into locking position while permitting free vertical movement of 85 said wedge plate.

201 denotes studs riveted to the ends of the resetting bars 32 and received in openings 202 in the wedge plates, 88, said openings being of a greater vertical width than 90 the studs 201 to permit the necessary vertical movement of the wedge plates, and being extended to the left, preferably to the edge of the plates, as shown, to permit independent movement to the left of the resetting bars as is necessary in split and restricted voting. Upon the return of the resetting bars to normal position the studs 201 cause the withdrawal of any wedge plate 88 which has been moved into locking position. 95

The plates 113 (see Fig. 3 also Fig. 3a) which are riveted to the resetting bars 32 are each provided with an upstanding arm 203 having an inclined end flange 205 and a second flange or offset portion 206. The 100 notches 114 may be formed by cutting away the metal of the bars and the arms 203 may be made integral with the bars, if preferred.

207 denotes angular lugs secured to the locking bar 84 in position to be engaged by 110 the inclines 205 when the resetting bars are moved to the left.

208 denotes dogs pivoted at 209 to brackets 210 secured to the framework. Each dog is formed with a substantially straight surface or edge 211 adapted to engage a notch in the offset 206 and terminating in a recess 212. A tooth 213 on each dog 208 is adapted to engage notches or teeth 214 in or on the corresponding link 84 for a purpose pres- 115 ently to be explained.

215 (Figs. 1 and 4) denotes a link connected to the arm 128 on the restricting shaft by a pivot 216.

217 is a double arm secured to releasing 125 shaft 131. The branches of arm 217 straddle a projection 218 formed on the right hand end of wedge bar 103 and carry a pin 219 which passes through a slot 220 in the projection 218 and through a slot 221 in the 130

link 215, said pin being provided with a head outside said link to retain the same in position.

- 140 denotes a lip at the left end of special resetting bar 33 which is adapted to be engaged by a lug 141 on the right end of the wedge bar, and also to engage an outwardly extending inclined lug 222 on a plate 223 which is riveted to vertical locking bar 34 to force said bar downward, should it not drop by gravity when released by the arms 203 on the resetting bars 32, when special resetting bar 33 is moved toward the right.
- 224 denotes an inclined lip at the right end of the wedge bar 103 adapted to engage an inclined surface 225 on the plate 223 to move locking bar 34 upwardly when wedge bar 103 is moved to the left.
- 226 denotes a dog pivoted on a fixed pivot 227 to the wedge bar 103 and provided with a projection 228 extending through a slot 229 in the link 215 and provided with a retaining washer 230 held in place by a cotter pin 231. The dog 226 when turned upwardly on its pivot, as will be more fully described, is adapted to be engaged by the lip 140 on the special resetting bar.

The resetting shaft 66 is journaled in the framework and in a bracket 232 (see Figs. 7 and 8) riveted thereto and is provided with a sleeve 235 between said framework and crank 68. Beyond the bracket 232 the shaft is provided with a spring 233 secured at one end to the bracket 232 and at the other in a slot in the end of shaft 66 by means of a cotter pin 234. The spring 233 serves to return the resetting lever 67 to its normal position after it has been operated. The crank 68 on the shaft 66 is made double to straddle the operating bar 35, the two arms of said crank being connected by a pin 236 passing through a slot 310 (see Fig. 8) in said bar.

237 denotes a manually operated latch pivoted on a stud 238 projecting from the framework and adapted to be turned from the position shown in full lines in Fig. 1, which position it occupies in ordinary elections, into the position shown in dotted lines in Fig. 1, and in full lines in Figs. 7 and 8 to lock the resetting mechanism.

239 (see Figs. 1 and 2) denotes an extension of the operating bar 35, provided at its upper end with a hook 240.

241 denotes a block riveted to the clutch controlling bar 148 and carrying a plate 242 to which is riveted a catch plate 243 which, when the bar 148 is moved to the left in Fig. 1, is adapted to be engaged by the hook 240.

244 (see Figs. 4, 5 and 9) denotes channel bars extending longitudinally of the interlocking members to support the same.

157 The cam plates 157 are received in the

grooves of the channel bars 244 while the side plates 158 rest upon spaced strips or flanges 245 with which said channel bars are provided.

200 (see Fig. 10) denotes the main operating shaft provided outside the casing with a main operating lever (shown in Fig. 1^a).

246 denotes an arm secured to the shaft 200 and to which is pivoted one end of a link 247 provided at its opposite end with an aperture 248.

249 denotes the main operating bar which is mounted for longitudinal reciprocation in suitable brackets 253, supported by the framework, and to which is secured a plate 250. The plate 250 is provided with an aperture 251 and with a pivoted latch 252. The apertures 248 and 251 are adapted to receive a detachable connecting pin 251^a which is retained in place by the latch 252, and when the parts are so connected oscillation of the shaft 200 will produce a corresponding reciprocation of the bar 249. In Fig. 10 these parts are shown in full lines in their normal connected position and in dotted lines in their disconnected position.

254 denotes counter grid operating shafts journaled in the brackets 253 and provided with pinions 255 (see Figs. 10 to 15) adapted normally to coöperate with rack teeth 256 formed on the main operating bar 249. When the pin 251^a is removed to disconnect the link 247 from the plate 250, the bar 249 may be moved longitudinally toward the right in Fig. 10 to carry the racks 256 out of mesh with the pinions 255, as shown in Figs. 14 and 15, for a purpose hereinafter explained.

257 (see Figs. 16^a and 18) denotes eccentrics fast on shafts 254 and having straps 258 which are connected with the counter grid or carrier, indicated by 311, which is not shown in detail as specifically it forms no portion of the present invention, but which may be substantially as shown and described in my former Letters Patent No. 873,401, dated Dec. 10, 1907. For the purposes of the present description, it will be sufficient to say that this counter grid carries a plurality of counters equal in number to the number of voting members 30. The voting members comprise dogs which are adapted to engage and disengage the corresponding counters when the voting members are moved into and out of the voted position.

At each actuation of main operating bar 249, as when a voter passes to or leaves the machine, movement is imparted to the counter grid, the entrance movement being necessarily an idle movement. At the exit movement of the counter grid, all counters which have been engaged by voting members are operated to record a vote.

259 denotes spiral gears fast on the shafts 254. The gear 259 shown at the right in Fig. 10 (see also Figs. 13, 14 and 15) is provided with a hub 260 having a recess 261 adapted to receive a pin 262 projecting from the main operating bar 249, the purpose of which is to serve as positioning means, *i. e.* to insure the engagement of the racks 256 with the pinions 255 in the proper relative position after the disengagement of these parts for setting the counters, as will be presently more fully described. It will be obvious that the rack 256 cannot be moved from the position shown in Figs. 14 and 15 into engagement with the pinion 255 except when the shaft 254 is in such an angular position that the pin 262 can enter the recess 261. The two shafts 254 are always connected for rotation in unison, so that it is necessary to provide the above described positioning means for one of these shafts only.

263 denotes spiral pinions meshing with the spiral gears 259 which are fixed to a counter setting shaft 264. The shaft 264 is journaled in the framework and is provided outside the casing with a squared end 265 adapted to receive a suitable socket wrench or crank.

266 denotes the paper feed shaft of the independent voting mechanism. Secured to the shaft 266 is a spiral gear 267 meshing with a spiral pinion or gear 268 formed on a sleeve 269 (see Figs. 16 and 19) loose on the shaft 254, but held against movement longitudinally thereof by the eccentric 257 and a collar 270 pinned to the shaft. The gear 267 is provided with an annular flange 271 having a portion cut away as indicated at 272.

273 denotes a sleeve having flanges or projections 274 embracing the gear 267 and held thereby against rotation. Engagement of one of the flanges 274 with the flange 271 prevents the sleeve 273 from moving upwardly except when said flange is opposite the cut away portion 272 as shown in Fig. 16.

275 denotes a clutch member having a shoulder 276 engaging the lower edge of the sleeve 273 and held thereby with its clutch face 277 in engagement with a complementary clutch face 278 formed on the eccentric 257. The clutch member 275 is transversely slotted to receive a flattened enlargement formed on the sleeve 269, as shown in Fig. 19, whereby the pinion 268 is rotated through said clutch member from the eccentric 257. With the parts in the position shown in Fig. 16, however, the clutch member 275 may be raised to unclutch the pinion from the shaft 254.

The restricting shaft (see Figs. 30 to 34) is herein shown as formed in two parts indicated specifically by the numerals 279 and

280, said parts being journaled in the framework and in a bracket 284. The ends of these parts are slightly separated and are provided with transverse slots 281 and 282 respectively. The arm 177 is secured to the part 279 and the arm 128 to the part 280.

283 denotes a sleeve connecting the ends of the parts 279 and 280 and provided with transverse pins 285 and 286 adapted to enter the slots 281 and 282 respectively, said pin 286 being extended outwardly to furnish means whereby said sleeve may be manually operated. The sleeve 283 is flattened or cut away for a portion of its length on one side, as indicated at 287, to co-operate with the straight edge of a flange 288 depending from an angular plate 289 riveted to the bracket 284 and having a portion extended downwardly to form a bearing for the sleeve 283. The normal position of the parts is shown in Fig. 31, in which the pins 285 and 286 are shown in position in the slots 281 and 282 and the two parts 279 and 280 of the shaft 126 therefore coupled by the sleeve 283. At this time the end of the sleeve 283 is engaged by the flange 288 and held thereby in operative or coupling position. Upon turning the restricting lever 127 to restricting position the flattened portion 287 of the sleeve 283 is brought opposite the edge of the flange 288. The sleeve may thereupon be moved to the right from the position shown in Fig. 31 to that shown in Fig. 30, the slot 282 being of a sufficient depth to permit this movement. This causes the pin 285 to be moved out of the slot 281 into the space between the ends of the shaft parts 279 and 280, thereby uncoupling these parts. It will be observed that the sleeve 283 is permanently connected with the part 280 by the continued engagement of the pin 286 in the elongated slot 282, so that when the sleeve has been moved to the right the engagement of the flange 288 with the flattened portion of the sleeve, causes the shaft part 280, the arm 128 thereon, and the mechanism controlled by said arm to be locked in restricting position.

The mechanism controlled by the arm 128 includes the releasing mechanism for the individual voting members and the wedge bar 103 for locking the party levers. The lever 127 may now be returned to non-restricting position. This causes the slot 281 to be turned out of alignment with the pin 285, thereby locking the sleeve 283 in uncoupling position, and causes the shaft part 279, the arm 177 thereon, and the mechanism controlled by said arm to be returned to non-restricting position. The mechanism controlled by the arm 177 includes the restricting members for locking the individual voting members.

204 (see Figs. 1, 3, 4, 20 to 23 and 35) denotes primary locking bolts or members. These bolts are equal in number to the num-

ber of lines of voting members, are guided in suitable parts of the framework, and are movable from an inoperative or retracted position into an operative position in which their rear ends shown at the left in Figs. 5 21 and 22 are adjacent the studs 201 riveted to the ends of the resetting bars 32. As shown in Fig. 3 the resetting bar 32 is in its extreme position toward the right, and the 10 corresponding bolt 204 when in operative position as shown in Fig. 35 serves to lock the bar 32 in this extreme position, and, by the engagement of the pins 165 with the ends of the slots 193, to lock the voting members in the corresponding line in non-voting 15 position.

290 (see Figs. 26 to 29) denotes a key bar or carrier slidably mounted in a guideway formed by the front of the machine casing, 20 through which the forward ends of the bolts 204 project, and a cover plate 291 secured thereto, said cover plate having an index opening 292.

293 (Fig. 25) denotes party markers arranged according to statutory provision and each designated by an identifying symbol, herein shown as letters "A," "B," "C," etc. The key bar 290 is shown as composed of three plates riveted together, the central 30 plate being provided with a series of projecting lugs or teeth 294. The lugs or teeth 294 may, for convenience, be considered as arranged in groups, there being a number of teeth in each group equal to the number of 35 party lines and the individual teeth of each group being designated on the key bar by symbols corresponding to the symbols displayed by the party markers, as clearly shown in Figs. 20, 26 and 27. The several 40 groups are further distinguished by designating characters, preferably numerals "2," "3," "4," etc.

295 denotes a shaft journaled in the framework and provided outside the casing 45 with an operating knob or handle 296. The shaft 295 carries a pinion 297 adapted to coöperate with rack teeth 298 formed on the key bar 290. By rotating the shaft 295 the key bar can be moved longitudinally to 50 bring any desired symbol opposite the index opening 292.

299 (Figs. 21 and 22) denotes a washer loosely surrounding the shaft 295 and fixed against rotation to the framework. 300 de- 55 notes a second washer mounted on the shaft 295 for rotation therewith but movable longitudinally thereof.

301 denotes a collar pinned to the shaft 295 and between which and the washer 300 60 is interposed a spring 302. The washers 299 and 300 are formed with interengaging angular recesses and projections and being held in yielding engagement by the spring 302 form a yielding lock for normally holding the shaft 295 in certain predetermined

angular positions. These positions are such as will hold the key carrier 290 with the symbols carried thereby exactly opposite the index opening 292. The shaft 295 is longitudinally movable in its bearings to carry 70 the pinion 297 into and out of engagement with the rack 298.

303 (Figs. 21 and 24) denotes a latch pivoted at 304 to the framework and provided with a projection 305 adapted to occupy a position between the collar 301 and the framework to hold the pinion 297 in engagement with the rack 298.

306 denotes a spring for normally holding the latch 303 in locking position. 80

307 denotes numbers carried by the key bar 290, which members, for convenience, I denominate "keys" since they perform the function of operating the locking bolts or members 204 to lock and unlock the respective lines of voting members, as will be explained. As shown the keys comprise flat strips of metal bent to form angular offsets or cam portions 308. The keys may be applied to the key carrier in any required 90 position and are held in place thereon by engagement with the teeth 294, the offset portion 308 embracing one of these teeth, as shown most clearly in Fig. 29. The primary locking members 204 are provided with 95 notches 309 adapted to receive the edges of the keys 307. The arrangement is such (see particularly Figs. 21 to 23) that when the straight portion of any key is in engagement with the notch 309 of the corresponding 100 locking member said member will be retracted or moved toward the left as shown in Figs. 21 and 22 into locking position with its rear end in a position to be engaged by the stud 201 on the resetting bar 32, as 105 shown in Fig. 35 thereby locking the corresponding party line. When the key carrier 290 is raised from the position shown in Fig. 22 into a position to bring the cam portion 308 into engagement with the notch 110 309 the locking member is projected forwardly or moved toward the right in Figs. 21 and 22 and the corresponding party line unlocked. The several keys 307 (see Fig. 27) are preferably provided with designat- 115 ing characters corresponding to the designating characters or numerals provided on the key carrier 290 to indicate the respective groups of teeth 294. The keys are applied to the key carrier in such a manner that 120 when the symbol "A" on the key carrier is opposite the index opening 292 party line "A" will be unlocked and the remaining party lines locked. When the knob 296 is turned to bring the symbol "B" opposite 125 the index opening party line "B" will be unlocked, party line "A" will be locked, and the other party lines will remain locked. In this manner any desired party line can be unlocked leaving all other party lines locked. 130

This, in the construction shown, is accomplished by placing key "1" with its offset portion 308 on the tooth 294 designated by "A" (as shown the first group of teeth is not indicated by numerals, which may, however, be applied if desired), the key "2" with its offset portion on the tooth "B²," the key "3" on the tooth "C³," and so on. Should any party occupy more than one line, the keys will be correspondingly arranged to cause both or all of these lines to be simultaneously locked and unlocked. For example, should the party "B" occupy the second and third lines, key "1" will be placed with its offset portion on tooth "A," key "2" on tooth "B²," key "3" on tooth "B³," key "4" on tooth "C⁴," and so on as will be obvious. In order that the keys may at all times be in engagement with their respective notches 309 these keys are preferably formed with their offset or cam portions 308 at a progressively varying distance from their upper ends, as shown most clearly in Fig. 27. In order to remove the key carrier from the machine for the purpose of arranging the keys, the latch 303 is raised permitting the spring 302 to move the pinion 297 out of engagement with the rack 298. The key carrier may then be withdrawn downwardly from beneath the cover plate 291.

The above described primary locking mechanism, *per se*, constitutes the subject matter of a divisional application filed January 12, 1912, Serial No. 669,252, and is not separately claimed herein, although said mechanism in its relationship to other parts of the machine as a whole constitutes a portion of the present invention, and to this end certain of the claims hereunto appended include features of said mechanism in combination with certain other features of the machine not covered by my divisional application aforesaid.

45 The main operating mechanism.—The machine is of course normally locked. This position of the parts is shown in Fig. 1. The first act of a voter is to operate entrance mechanism which oscillates the main operating shaft 200 (see Fig. 10) and raises the cam bar 36 from the position shown in Fig. 1. The means for operating the shaft 200 and the connections between this shaft and the cam bar 36 are not shown as they form no part of the present invention. As the cam bar moves upward the cam slots 38 will move the links 44 to the left, the pins 47 (see Fig. 1) moving in the slots 48, and will also, by means of links 190, move special resetting bar 33 to the left to release the locking bar 34. During the latter portion of the upward movement of the cam bar the pins 54 will be engaged by the lower ends of the slots 37 and the latches 50 raised to unlock the resetting bars. This

oscillation of the shaft 200 also causes the main operating bar 249 to be moved longitudinally toward the left in Fig. 10, the counter grid operating shafts 254 to be turned by the racks 256 and pinions 255 and the counter grid to make its idle movement and the paper feed shaft 266 to be turned by the pinion 268 into the position shown in Figs. 11, 16 and 17, the paper feed mechanism being, of course, disconnected. When the voter leaves the machine after having cast his vote, he operates exit mechanism which turns the shaft 200 back to its normal position and lowers the cam bar 36. The effect of this movement is, by means of links 44 and 190, to return the party bars, resetting bars and special resetting bar 33 to their normal positions by movement to the right, and also through the engagement of pins 165 of the voting members with slots 193 in the resetting bars to return all operated voting members to their normal position, to withdraw any operated wedge plate 88 or the wedge bar 103, if it has been operated, leaving the wedge system unlocked, to draw down locking bar 34, if it does not drop, and with its extension 143, thereby locking the independent voting shutters, and to lower catches 109 into engagement with the notches 114 on the resetting bars, and also to lower the latches 50 to lock the party bars. This return movement of the shaft 200 also causes the main operating bar 249 to be moved toward the right, which causes rotation of the shafts 254 and 266. Rotation of shafts 254 causes actuation of the counter grid and consequent operation of the counters corresponding to such voting members as have been moved to the voting position. Rotation of shaft 266 causes operation of the paper feed mechanism if the clutch controlling bar 148 has been moved to the left in Fig. 1 by the opening of an independent shutter. The setting of the voting mechanism for causing the above operations upon the return of the main operating bar 249 to normal position will now be described.

45 The voting operation.—The voter having operated the entrance mechanism, as above described, and entered the voting booth, let us suppose, first, that he desires to vote a straight party ticket; second, that he desires to scratch or split; and, third, that he desires to vote for a portion only of the offices to be voted for, or scattering, or independently. When a party lever is operated, *i. e.*, pulled, its inner arm 81, by engagement with the link 84 connected with the corresponding party bar, causes said party bar to be operated which carries all the voting members in that particular line to the voting position and causes the lugs 155 of the voting members to engage the corresponding interlocking members, thereby locking the voting members in all other party lines and also

the independent voting mechanism in non-voting position, as heretofore explained. The movement of the link 84 to the left causes said link to move the corresponding wedge plate 88 toward the left, thereby locking all of the other party levers in non-voting position, as already explained. During the movement of the party bar toward the left the catch 109 will ride up the incline 107 5 clearing the notches 114 on the resetting bar and leaving said bar unlocked and free to be moved toward the left by a voting member. At this time the flange 205 on the arm 203 comes in contact with the angular lug 207 and gives an additional upward movement to the locking bar 34. The last effect 10 of this movement is to unlock all other party lines and the independent voting mechanism by raising the catches 109 and extension 143, thereby permitting split voting. This 15 unlocking does not take place, however, until the slack is taken out of the interlocking members, so that it is impossible at this moment to operate a voting member in some 20 other party line. As soon as the catch 109 corresponding with the operated party bar starts up the incline it commences to raise locking bar 34, through the engagement of stud 112 with aperture 111 in the locking 25 bar. The first portion of this movement, however, does not raise the catches 109 of the other party lines, which are not raised until the locking bar has moved upwardly sufficiently to cause the lower sides of apertures 30 111 to engage the corresponding studs 112. When the locking bar is raised by the operation of a party lever, extension 143 is raised also and the hooked upper end 146 thereof is 35 raised above the projection 147 on the clutch 40 controlling bar 148 of the paper feed mechanism, permitting this bar to be moved to the left by the opening of an independent shutter. (Not shown.) It will of course be understood that the interlocking member 45 prevents the opening of an independent shutter when any of the regular voting members in the same office column is in voting position. This is not fully illustrated herein, as it forms no part of the present invention. 50 Having cast a straight party vote the voter should he desire to scratch any of the candidates of his party does so by moving the voting members corresponding with the candidates for whom he does not desire to vote 55 from the voting position to which they have been moved by the party lever and party bar to the non-voting position. This movement is permitted by the slots 193 in the corresponding resetting bar. Should he desire to 60 split, that is, cast votes for candidates of another party, he does so by moving the corresponding voting members from the non-voting to the voting position. This movement is permitted by the slots 192 in the 65 party bars. It will of course be understood

that having scratched a candidate he relieves the tension on the corresponding interlocking member so that a vote may be cast for any other candidate for the same office.

In order to prevent a voter who has voted 70 a party ticket and then split upon one or more candidates of his party from afterward operating the same party lever again, the dogs 208 are provided. These dogs engage teeth 214 on the links 84 corresponding 75 with actuated party bars, and are provided with surfaces 211 which are engaged by offsets 206 of arms 203 extending from the resetting bars 32. When the party bar is moved toward the left by operation of the 80 party lever, the corresponding link 84 moves to the left beyond dog 208 before offset 206 passes into the recess 212 and permits the dog to drop down far enough to engage the teeth, but when a voter scratches a candidate 85 for whom he has already voted, the return of the corresponding voting member from the voting to the non-voting position will, through the engagement of the pin 165 of the voting member with the slot 192 in the 90 party bar, move said bar to the right far enough to permit the dog to engage the teeth 214 on the link 84, and thus render it impossible to again operate the party bar by means of the party lever unless the mechanism 95 be reset as hereinafter described.

The releasing mechanism.—Should a voter not wish to vote any party ticket but prefer to vote scattering for the candidates of different parties or to vote for candidates for 100 a part only of the offices to be voted for, he is not obliged to operate a party lever 76 but may operate the releasing lever carried by the releasing shaft 131, the effect of which is to lock all the party levers and to 105 unlock all the voting members. The pin 219 carried by the arm 217 on the releasing shaft is at the left end of slot 220 in the projection 218 of the wedge bar 103. When the releasing shaft is turned from right to 110 left by the releasing lever wedge bar 103 is moved toward the left which locks the wedge system and makes it impossible to operate any party lever. At the same time the lip 224 on the wedge bar raises the locking bar 34, and an instant after the locking 115 of the party levers by means of the wedge system studs 112 carried by double catches 109 will be engaged by the lower walls of apertures 111 in the locking lever and continued movement of the releasing lever and the locking bar 34 will raise all of the catches 109 and release the party bars, leaving all the voting members and the independent mechanism free to be operated. It 120 will be seen that after the releasing lever has been operated it will be impossible to return the same and unlock the party levers or to lower locking bar 34 as the pin and slot connection between the arm 217 and 125 130

wedge plate 103 renders this impossible, the pin 219 merely moving in the slot 220 when the releasing lever is operated, but without imparting movement to the wedge bar and locking bar.

The resetting mechanism.—This mechanism is provided in order to enable a voter who changes his mind and wishes to change his entire vote to return all operated voting mechanism to its normal or non-voting position without operation of the counters by operating the resetting lever 67. The effect of this would be to reset the voting members and the party levers and to unlock the wedge system, which would be otherwise impossible, as the releasing of the voting members to their non-voting positions, *i. e.*, scratching, would not unlock the wedge system and enable him to operate another party lever. Operation of the resetting lever and shaft 66 by means of crank 68 draws down operating bar 35 which is provided with slots 61 corresponding with the party lines. When a party bar is operated the corresponding bell crank lever 59 is turned on its pivot from left to right by means of the dog 57 which is secured to the resetting bar and engages one arm of said lever. This does not change the position of the operating bar, but carries cross pin 60 to the upper end of slot 61 so that when the resetting lever is operated the operating bar will swing the bell crank lever back to the position shown in Fig. 1 and return the resetting bars to their normal position through the engagement of said lever with the dogs 57 secured to said bars. The downward movement of the operating bar also acts to move special resetting bar 33 toward the right through the engagement of cam projection 70 on the operating bar with lug 71 on the bar 33. The special resetting bar in turn acts to return locking bar 34 to its normal position through the engagement of lip 140 on bar 33 with lug 222 extending from plate 223 which is rigidly secured to the locking bar. And furthermore bar 33 withdraws wedge bar 103, if it has been operated, through the engagement of lip 140 with the lug 141 on the wedge bar, thus leaving the entire machine as it was before the operation of a party lever or the releasing lever, provided, however, that the voter has not opened an independent shutter. If a voter elects to vote independently, that is, not for the candidates of any party, but upon a ticket of his own making, which he must do by means of the independent voting mechanism which specifically forms no portion of the present invention, he must open one or more of the independent shutters (not shown). The opening of an independent shutter moves the clutch controlling slide 148 for the paper feed mechanism toward the left, causing projection 147 to pass under

hook 146 on extension 143 of locking bar 34 and causing catch plate 243 to pass under hook 240 on extension 239 of the operating bar 35. Thereafter it is impossible to unlock the wedge system or to operate the resetting mechanism in any manner until the operation of the exit mechanism when the voter leaves the machine. In other words, it is impossible for a voter to vote independently and thereafter operate the resetting lever and cast a second vote by means of the regular voting mechanism.

The restricting mechanism.—The restricting lever 127 lies outside the casing of the machine on the front. When a voter of limited franchise, that is, one who is entitled to vote for candidates for certain offices only, approaches the machine the custodian operates the restricting lever, the effect of which is to turn shaft 126 and operate arm 177 thereon, said arm being connected with mechanism heretofore described for locking the voting members in the office columns on which the restricted voter is not entitled to vote. The restricting shaft also carries arm 128 which is pivoted to the link 215, said link having slots receiving studs carried respectively by the arm 217 on the releasing shaft and by the dog 226 pivoted to the wedge bar 103. When the custodian operates the restricting lever he causes the link 215 to be lifted, thereby swinging the dog 226 upwardly and bringing its right end into the path of movement of the lip 140 at the left end of special resetting bar 33. When the voter operates the entrance mechanism and raises cam bar 36, special resetting bar will be moved toward the left. The effect of this movement will be to move the dog 226, and with it the wedge bar 103, toward the left. The movement of the wedge bar locks the wedge system and by the engagement of its lip 224 with the plate 223 raises the bar 34, thereby unlocking the voting members. It will be apparent that owing to the loose connection between the link 215 and the dog 226 the restricting mechanism will not be returned to normal position by the downward movement of the cam bar caused by operation of the exit mechanism when the restricted voter leaves the machine, and so long as restricted voters continue to vote the custodian has nothing further to do. It will of course be understood that when a restricted voter leaves the machine the lowering of the cam bar by the exit mechanism withdraws wedge bar 103 and lowers locking bar 34 in precisely the same manner as when a voter with unlimited franchise leaves the machine, the only difference being that after a restricted voter has voted if the next voter is a restricted voter no operation of the restricting lever is required, but if the next voter is a non-restricted voter the custodian must return

the restricting lever to its normal position and throw off the restriction before the non-restricted voter operates the entrance mechanism and raises the cam bar. It will also 5 be obvious that owing to the pin and slot connection between the link 215 and arm 217 operation of the releasing mechanism in ordinary voting will have no effect on the restricting mechanism.

10 *The counter setting mechanism.*—After the polls have been closed and the vote recorded by the proper authorities it is necessary, in order to prepare the machine for another election, to reset the counters. This 15 is done by the mechanism illustrated in Figs. 10 to 19. The entrance mechanism is first operated to oscillate the main operating shaft 200, thereby raising the cam bar 36 to unlock the voting members and causing the 20 counter grid operating shafts 254 and paper feed shaft 266 to be turned into the relative positions shown in Figs. 11, 16 and 17 with the cut away portion 272 of the flange 271 opposite the flange 274. The latch 252 is 25 swung aside and the pin 251^a removed from the apertures 248 and 251 to disconnect the bar 249 from the shaft 200. The clutch member 275 is raised to disconnect the pinion 268, and consequently the paper feed 30 shaft, from the counter grid operating shaft 254. One line of voting members is then put into voting position, which places them in engagement with the corresponding counters. A suitable crank is then applied 35 to the squared end 265 of the shaft 264 and turned. The first effect is to move the racks 256 entirely out of engagement with the pinions 255 and into substantially the position shown in Figs. 14 and 15. The shaft 264 40 is then continuously rotated in either direction causing the counters to be simultaneously actuated. The direction of rotation of the crank, in order that the counters may be most quickly reset, will depend upon 45 whether the average number registered by the counters in the line being reset is greater or less than one-half the capacity of said counters. Ordinarily this number will be less, in which case it will be easier and 50 quicker to turn the counters backwardly to zero than to reset them by turning them ahead. The crank is therefore given a number of turns in the proper direction to turn the counters backwardly equal to the lowest 55 number registered by any of the counters in the line being reset, bringing the corresponding counter to zero. The voting member controlling this counter is then moved to the non-voting position. The voting members 60 controlling any other counters in said line which at this time register numbers less than ten may also, if desired, be moved to the non-voting position, leaving the unit members of these counters to be reset by 65 hand. The crank is again turned and other

voting members are moved to the non-voting position as the corresponding counters reach or approach zero, as will be understood from the foregoing description. It will also be understood that if the crank be 70 rotated in a direction to cause the counters to be turned forwardly, the voting members are, in the same manner, moved to the non-voting position when the corresponding counters reach zero. When all of the 75 counters in one party line have been reset, another line may be reset in the same manner. This operation is continued until all of the counters of the machine have been reset to zero, whereupon the parts are again 80 connected, as will be obvious from the foregoing description, and the exit mechanism operated to return the shaft 200 to normal position, thereby lowering the cam bar 36 and locking the voting mechanism. 85

The primary locking mechanism.—In order to adapt the machine for primary voting it is necessary to lock all party levers against the voter and also to lock all lines of individual voting members except those 90 occupied by the candidates of the party for whom the voter is entitled to vote. The locking of the party levers is accomplished as follows, reference being had to Figs. 30 to 35 in connection with Figs. 1 and 4. The 95 restricting lever 127 is turned to restricting position, thereby swinging the dog 226 upwardly into the path of movement of the lip 140 on special resetting bar 33. When a primary voter operates the entrance mechanism on entering the machine the cam bar 36 moves special resetting bar 33 to the left and through the lip 140 and dog 226 carries wedge bar 103 into position to lock the 100 wedge system and the party levers. Of course it will be understood that when a primary voter leaves the machine the operation of the exit mechanism causes the wedge bar 103 to be withdrawn, but so long as the dog 226 remains in elevated position the wedge 105 system will be locked whenever the entrance mechanism is operated, substantially as above described in connection with the restricting mechanism. Movement of wedge bar 103 to the left also causes, by engagement of the lip 224 with the inclined edge of the plate 223, the elevation of the locking bar 34 to unlock the party lines. In order to prevent a primary voter from operating the resetting lever and unlocking the 110 party levers the latch 237 is turned into the position shown in dotted lines in Fig. 1, thereby locking the operating bar 35 against movement by the resetting lever. Operation of the restricting lever as above described 115 has brought the flattened portion 287 of the sleeve 283 opposite the flange 288 and has also, through the arm 177, operated the mechanism for locking the voting members 120 in certain office columns. To release these 125 members the voter must turn the crank 130

voting members the sleeve 283 is slid to the right, thereby disconnecting the parts 279 and 280 of the shaft 126 and locking the part 280 and the arm 128 in restricting position. The lever 127, together with the shaft part 279 and arm 177, is then returned to non-restricting position. By this mechanism the party levers are all locked against the voter and all the individual voting members are unlocked. It therefore remains to lock all lines of voting members except those occupied by the candidates of the party for whom the voter is entitled to vote. This is done by the primary locking mechanism proper, shown in Figs. 20 to 29 and 35. (See also Figs. 3 and 4). Let it be assumed that the party markers 293 have been put in place and the keys 307 applied to the key bar 290 in accordance with the requirements and as heretofore fully explained. The knob 296 is then turned until the symbol corresponding to the party in question appears at the index opening 292. When this occurs the primary locking member or members 204 which control the line or lines of voting members occupied by the party in question have been withdrawn by the engagement of the cam portions 308 of the corresponding keys with the notches 309 of said bolts, while all other locking members are held by the straight portion of the corresponding keys with their rear ends in a position to engage the studs 201 carried by the resetting bars 32 of the other party lines, as shown in Fig. 35, thereby locking all voting members except those in the lines occupied by the candidates for whom the primary voter is entitled to vote.

Having thus described my invention, I claim:—

1. The combination with lines of voting members, of members actuated by any voting member in a line and having locking means, catches adapted to engage the locking means to lock the voting members in each line, means to release a catch to unlock the voting members in the corresponding line, and means operated independently of the released catch to release the other catches and unlock the voting members in the other lines.

2. The combination with lines of voting members, of members actuated by any voting member in a line and having locking means, catches adapted to engage the locking means to lock the voting members in each line, a locking bar connecting said catches, means to release a catch to unlock the voting members in the corresponding line, and means independent of the released catch for operating said locking bar to release the other catches and unlock the voting members in the other lines.

3. The combination with lines of voting

members, of members actuated by any voting member in a line and having locking means, catches adapted to engage the locking means to lock the voting members in each line, means to release a catch to unlock the voting members in the corresponding line, and means operated independently of the released catch by the member which is actuated by the voting members in that line to release the other catches and unlock the voting members in the other lines. 75

4. The combination with party bars having inclines and resetting bars having notches, of catches adapted to engage the notches to lock the resetting bars and to be raised by an incline when a party bar is operated, and means operated independently of the raised catch by the corresponding resetting bar to raise the other catches. 80

5. The combination with lines of voting members, of members actuated by any voting member in a line and having locking means, catches adapted to engage the locking means to lock the voting members in each line, a locking bar connecting said catches, means to release a catch to unlock the voting members in the corresponding line, and means carried by the member which is actuated by the voting members in that line for engaging and operating said locking bar to release the other catches and unlock the voting members in the other lines. 95

6. The combination with lines of voting members, of members actuated by any voting member in a line and having locking means, catches adapted to engage the locking means to lock the voting members in each line, a locking bar connecting said catches, an angular lug on said locking bar, means to release a catch to unlock the voting members in the corresponding line, and an arm projecting from the member which is actuated by the voting members in that line, said arm having an inclined end for engaging said angular lug and operating said locking bar to release the other catches and unlock the voting members in the other lines. 100

7. The combination with voting members, party levers, party bars, links engaged by the party levers and having notches, studs connecting the links and the party bars, and resetting bars having elongated slots through which the studs pass, of dogs adapted to engage the notches in the links to lock said party bars against a second forward movement after a return movement, and means on said resetting bars for engaging and controlling said dogs. 115

8. The combination with voting members, party levers, party bars, links engaged by the party levers and having notches, studs connecting the links and the party bars, and resetting bars having elongated slots

- through which the studs pass, of dogs adapted to engage the notches in the links to lock said party bars against a second forward movement after a return movement, and 5 means on said resetting bars to hold said dogs out of engagement with said notches until said resetting bars have been operated.
9. The combination with voting members, party levers, party bars, links engaged by the party levers and having notches, studs connecting the links and the party bars, and resetting bars having elongated slots through which the studs pass and projecting arms having offsets, of dogs engaged by said 10 offsets and adapted to engage the notches in the links to lock said party bars against a second forward movement after a return movement.
10. The combination with voting members, party levers, party bars, links engaged by the party levers and having notches, studs connecting the links and the party bars, and resetting bars having elongated slots through which the studs pass, of dogs 15 having edges terminating in recesses and adapted to engage the notches in the links to lock said party bars against a second forward movement after a return movement, and means carried by said resetting bars to normally engage said edges and hold said 20 dogs out of engagement with said notches, said means passing into said recesses and releasing said dogs when said resetting bars are operated.
- 35 11. The combination with voting members, party levers, party bars, links engaged by the party levers and having notches, studs connecting the links and the party bars, and resetting bars having elongated 40 slots through which the studs pass, of dogs having edges terminating in recesses and adapted to engage the notches in the links and lock said party bars against a second forward movement after a return movement, and arms projecting from said resetting bars and having offsets adapted normally to engage said edges and hold said dogs out of engagement with said notches, said offsets passing into said recesses and releasing said dogs when said resetting bars 45 are operated.
12. The combination with voting members, party levers, party bars having unlocking means, links engaged by the party levers 55 and having notches, studs connecting the links and the party bars, and resetting bars having locking means and elongated slots through which the studs pass, of catches adapted to engage the locking means of the 60 respective resetting bars and to be released by the unlocking means of the corresponding party bars, dogs adapted to engage the notches in the links to lock said party bars against a second forward movement after a
- return movement, and means carried by said 65 resetting bars for engaging and controlling said dogs and for releasing all of said catches.
13. The combination with voting members, party levers, party bars having unlock- 70 ing means, links engaged by the party levers and having notches, studs connecting the links and the party bars, and resetting bars having locking means and elongated slots through which the studs pass, of 75 catches adapted to engage the locking means of the respective resetting bars and to be released by the unlocking means of the corresponding party bars, a locking bar connecting said catches, angular lugs on said 80 locking bar, dogs adapted to engage the notches in the links to lock said party bars against a second forward movement after a return movement, and arms projecting from said resetting bars, said arms having in- 85 clined ends for engaging said angular lugs and operating said locking bar to release all the catches and having offsets for engaging and controlling said dogs.
14. The combination with voting mem- 90 bers, party levers, party bars, links engaged by the party levers and having each a series of teeth, studs connecting the links and the party bars, and resetting bars having elongated slots through which the studs pass, 95 of dogs adapted to engage the teeth on the links to lock said party bars against a second forward movement after a return move- ment.
15. The combination with voting mem- 100 bers, party levers, party bars, links engaged by the party levers and having each a series of teeth, studs connecting the links and the party bars, and resetting bars having elongated slots through which the studs pass, 105 of dogs adapted to engage the teeth on the links to lock said party bars against a second forward movement after a return move- ment, and means on said resetting bars for controlling said dogs. 110
16. The combination with party bars, party levers, links connected to the party bars and actuated by the party levers, and resetting bars, of a wedge system for locking the party levers including wedge plates 115 operated in one direction by said links and in the opposite direction by said resetting bars.
17. The combination with party bars, party levers, links connected to the party 120 bars and actuated by the party levers, and resetting bars, of a wedge system for locking the party levers including wedge plates moved into locking position by said links and withdrawn by said resetting bars. 125
18. The combination with party bars, party levers, and links connected to the party bars and actuated by the party levers,

of a wedge system for locking the party levers including wedge plates disconnected from said links but arranged to be engaged by the ends thereof and moved into locking position when said links are actuated by the party levers.

19. The combination with party bars, party levers, and resetting bars, of a wedge system for locking the party levers including wedge plates loosely connected to said resetting bars.

20. The combination with party bars, party levers, and resetting bars having studs, of a wedge system for locking the party levers including wedge plates having openings to receive said studs, said openings being of greater dimensions in both directions than said studs.

21. The combination with party bars, party levers, links connected to the party bars and actuated by the party levers, and resetting bars having studs, of a wedge system for locking the party levers including wedge plates disconnected from said links but arranged to be engaged by the ends thereof and moved into locking position when said links are actuated by the party levers, said wedge plates having openings to receive said studs, whereby they are withdrawn by said resetting bars.

22. The combination with voting members, party levers, and connections between the party levers and voting members, of catches adapted to lock the voting members, a locking bar by which the catches are released to unlock the voting members, a wedge system for locking the party levers including a wedge bar, a releasing shaft connected with said wedge bar, and means for operating said locking bar from said wedge bar.

23. The combination with voting members, party levers, and connections between the party levers and voting members, of catches adapted to lock the voting members, a locking bar by which the catches are released to unlock the voting members, a wedge system for locking the party levers including a wedge bar, and a releasing shaft connected with said wedge bar, said wedge bar and locking bar having coöperating cam surfaces.

24. The combination with voting members, party levers, and connections between the party levers and voting members, of catches adapted to lock the voting members, a locking bar by which the catches are released to unlock the voting members, a wedge system for locking the party levers including a wedge bar, a releasing shaft connected with said wedge bar, an inclined lip on said wedge bar, and a plate on said locking bar having an inclined edge coöperating with said lip.

25. The combination with voting members, of a resetting shaft, an arm on said

shaft, an operating bar directly connected with said arm, and connections between said operating bar and the voting members, actuation of the resetting shaft acting to reset all operated voting members.

26. The combination with voting members, of a resetting shaft, an arm on said shaft, an operating bar, a pin and slot connection between said arm and operating bar, and connections between said operating bar and the voting members, actuation of the resetting shaft acting to reset all operated voting members.

27. The combination with voting members, of a resetting shaft, an operating bar connected therewith, and connections between said operating bar and the voting members, actuation of the resetting shaft acting to reset all operated voting members, and a spring for returning said shaft and operating bar to normal position after said shaft has been actuated.

28. The combination with voting members, party levers, and connections between the party levers and voting members, of locking mechanism for the voting members, locking mechanism for the party levers, and direct connections between said locking mechanisms whereby one is operated from the other.

29. The combination with voting members, party levers, and connections between the party levers and voting members, of locking mechanism for the voting members, locking mechanism for the party levers, means for operating said last named locking mechanism, and means carried by said last named locking mechanism for engaging and operating said first named locking mechanism, whereby when said last named locking mechanism is locked said first named locking mechanism is unlocked.

30. The combination with voting members, party levers, and connections between the party levers and voting members, of locking mechanism for the voting members, locking mechanism for the party levers, a releasing shaft connected with said last named locking mechanism, and means whereby said first named locking mechanism is operated by said last named locking mechanism.

31. The combination with voting members, party levers, and connections between the party levers and voting members, of locking mechanism for the voting members including a bar having an inclined surface, and locking mechanism for the party levers including a bar having an inclined lip coöperating with said inclined surface.

32. The combination with voting members, party levers, and connections between the party levers and voting members, of locking mechanism for the voting members including a bar having an inclined surface, locking mechanism for the party levers includ-

- ing a bar having an inclined lip coöperating with said inclined surface, and a releasing shaft connected with said last named bar.
33. The combination with voting members, and party levers, of locking mechanism for the voting members, locking mechanism for the party levers, direct connections between said locking mechanisms whereby one is operated from the other, a resetting shaft, an arm on said shaft, an operating bar directly connected with said arm, connections between said bar and the voting members whereby actuation of said shaft causes all operated voting members to be reset, and connections between said bar and said locking mechanisms.
34. The combination with voting members and party levers, of locking mechanism for the voting members including a bar having an inclined surface, locking mechanism for the party levers including a bar having an inclined lip coöperating with said inclined surface, a releasing shaft connected with said last named bar, a resetting shaft, an arm on said shaft, an operating bar directly connected with said arm, connections between said operating bar and the voting members whereby actuation of said shaft causes all operated voting members to be reset, and connections between said operating bar and the bars of said locking mechanisms.
35. The combination with voting members and party levers, of locking mechanism for the voting members, locking mechanism for the party levers, and a member having a single part for engaging and actuating both said mechanisms to lock said first named mechanism and unlock said last named mechanism.
36. The combination with voting members and party levers, of locking mechanism for the voting members including a bar having a projection, locking mechanism for the party levers including a bar having a projection, and a member having a single part adapted to engage both of said projections to actuate both said mechanisms.
37. The combination with voting members and party levers, of catches adapted to lock the voting members, a locking bar by which the catches are released to unlock the voting members said bar having a projection, a wedge system for locking the party levers including a wedge bar having a projection, and a member having a single part adapted to engage both said projections to return said catches to locking position and unlock said wedge system.
38. The combination with voting members and party levers, of locking mechanism for the voting members, locking mechanism for the party levers, and a special resetting bar having a projection for engaging and actu-
- ating both said mechanisms to lock said first named mechanism and unlock said last named mechanism.
39. The combination with voting members and party levers, of locking mechanism for the voting members including a bar having a projection, locking mechanism for the party levers including a bar having a projection, and a special resetting bar having a projection adapted to engage both of said first named projections to actuate both said mechanisms.
40. The combination with voting members and party levers, of catches adapted to lock the voting members, a locking bar by which the catches are released to unlock the voting members said bar having a projection, a wedge system for locking the party levers including a wedge bar having a projection, and a special resetting bar having a projection adapted to engage both said first named projections to return said catches to locking position and unlock said wedge system.
41. The combination with voting members and party levers, of locking mechanism for the voting members including a bar provided with a plate having an inclined flange, locking mechanism for the party levers including a bar having a lug, and a special resetting bar having a lip adapted to engage said flange and lug to actuate both said mechanisms.
42. The combination with voting members and party levers, of catches adapted to lock the voting members, a locking bar by which the catches are released to unlock the voting members, a plate secured to said bar and having an inclined flange, a wedge system for locking the party levers including a wedge bar having a lug, and a special resetting bar having a lip adapted to engage said flange and lug to return said catches to locking position and unlock the wedge system.
43. The combination with lines of voting members and party levers, of members actuated by any voting member in a line and having locking means, catches adapted to engage the locking means to lock the voting members in each line, a locking bar connecting said catches and having a projection, locking mechanism for the party levers including a bar having a projection, means to release a catch to unlock the voting members in the corresponding line, means operated independently of the released catch for actuating said locking bar to release the other catches and unlock the voting members in the other lines, and a member having a single part adapted to engage both said projections to return all of said catches to locking position and unlock the party levers.
44. The combination with voting members and party levers, of locking mechanism for

the voting members, locking mechanism for the party levers, a resetting shaft, an arm on said shaft, an operating bar directly connected with said arm, connections between 5 said operating bar and the voting members whereby actuation of said shaft causes all operated voting members to be reset, and a special resetting bar operated by said operating bar, said resetting bar having a projection for engaging and actuating both said locking mechanisms to lock said voting members in reset position and to unlock said party levers.

45. The combination with voting members 15 and party levers, of locking mechanism for the voting members, locking mechanism for the party levers, direct connections between said locking mechanisms whereby one is operated from the other, and a member having 20 a single part for engaging and actuating both said locking mechanisms to lock said voting members and unlock said party levers.

46. The combination with voting members 25 and party levers, of locking mechanism for the voting members, locking mechanism for the party levers, means for operating said last named locking mechanism, means carried by said last named locking mechanism for engaging and operating said first named 30 locking mechanism whereby when said party levers are locked said voting members are unlocked, and a member having a single part for engaging and actuating both said locking mechanisms to lock said voting 35 members and unlock said party levers.

47. The combination with voting members 40 and party levers, of catches adapted to lock the voting members, a locking bar by which the catches are released to unlock the voting members said bar having a projection, a wedge system for locking the party levers including a wedge bar having a projection, a releasing shaft connected with said wedge bar, means carried by said wedge bar for 45 engaging and operating said locking bar, and a member having a single part adapted to engage both said projections to return said catches to locking position and unlock said wedge system.

50. 48. The combination with voting members 55 and party levers, of locking mechanism for the voting members including a bar having a projection, locking mechanism for the party levers including a bar having a projection, direct connections between said locking mechanisms whereby one is operated from the other, and a member having a single part adapted to engage both of said 60 projections to actuate both of said mechanisms.

49. The combination with voting members 65 and party levers, of locking mechanism for the voting members including a bar having a projection, locking mechanism for the party levers including a bar having a projection,

means carried by said last named locking mechanism for engaging and operating said first named locking mechanism, and a member having a single part adapted to engage both of said projections to actuate both of 70 said mechanisms.

50. The combination with voting members and party levers, of catches adapted to lock the voting members, a locking bar by which the catches are released to unlock the voting 75 members said bar having a projection, a wedge system for locking the party levers including a wedge bar having a projection, said wedge bar and locking bar having co-operating cam surfaces, and a member 80 having a single part adapted to engage both said projections to return said catches to locking position and unlock said wedge system.

51. The combination with voting members 85 and party levers, of locking mechanism for the voting members including a bar having an inclined surface, locking mechanism for the party levers including a bar having an inclined lip co-operating with said inclined 90 surface, and a member having a single part for engaging and actuating both said mechanisms to lock said voting members and unlock said party levers.

52. The combination with voting members 95 and party levers, of locking mechanism for the voting members, locking mechanism for the party levers, direct connections between said locking mechanisms whereby one is operated from the other, and a special resetting 100 bar having a projection for engaging and actuating both said mechanisms to lock said voting members and unlock said party levers.

53. The combination with voting members 105 and party levers, of locking mechanism for the voting members including a bar provided with a plate having an inclined flange, locking mechanism for the party levers including a bar having a lug, direct connections between said locking mechanisms whereby one is operated from the other, and a special resetting bar having a lip adapted 110 to engage said flange and lug to actuate both said mechanisms.

54. The combination with voting members 115 and party levers, including a bar having an inclined surface, locking mechanism for the party levers including a bar having an inclined lip co-operating with said inclined 120 surface, and a special resetting bar having a projection for engaging and actuating both said mechanisms to lock said voting members and unlock said party levers.

55. The combination with voting members 125 and party levers, of locking mechanism for the voting members including a bar, a plate secured to said bar and having an inclined surface and an inclined flange, locking mechanism for the party levers including a bar 130

- having an inclined lip coöperating with said inclined surface and a lug, and a special resetting bar having a lip adapted to engage said flange and lug to actuate both said mechanisms.
56. The combination with voting members and party levers, of locking mechanism for the voting members, locking mechanism for the party levers, a releasing shaft, a single arm on said shaft, and connections whereby actuation of said arm operates both said mechanisms.
57. The combination with voting members and party levers, of locking mechanism for the voting members, locking mechanism for the party levers, a releasing shaft, a single arm on said shaft, connections whereby actuation of said arm operates both said mechanisms, and a second member having a single part for engaging and operating both said mechanisms.
58. The combination with voting members and party levers, of locking mechanism for the voting members, locking mechanism for the party levers, a releasing shaft, a single arm on said shaft, connections whereby actuation of said arm operates both said mechanisms to lock said party levers and unlock said voting members, and a second member having a single part for engaging and operating both said mechanisms to lock said voting members and unlock said party levers.
59. The combination with voting members and party levers, of locking mechanism for the voting members, locking mechanism for the party levers, a releasing shaft, a single arm on said shaft, connections whereby actuation of said arm operates both said mechanisms, and a special resetting bar having a projection for engaging and actuating both said mechanisms to lock said voting members and unlock said party levers.
60. The combination with voting members and interlocking members, of means adjacent said interlocking members and arranged longitudinally thereof for supporting the same.
61. The combination with voting members and interlocking members comprising cam plates, side plates, and stud and slot connections between said plates acting to shorten the member when a cam plate is moved laterally, of means adjacent said interlocking members and arranged longitudinally thereof for supporting the same.
62. The combination with voting members and interlocking members comprising cam plates, side plates, and stud and slot connections between said plates acting to shorten the member when a cam plate is moved laterally, of channel bars arranged adjacent said interlocking members for supporting the same and having grooves to receive said cam plates.
63. The combination with voting members and interlocking members comprising cam plates, side plates, and stud and slot connections between said plates acting to shorten the member when a cam plate is moved laterally, of means for supporting said interlocking members including spaced strips engaged by said side plates.
64. The combination with voting members and interlocking members comprising cam plates, side plates, and stud and slot connections between said plates acting to shorten the member when a cam plate is moved laterally, of channel bars arranged adjacent said interlocking members for supporting the same and having grooves to receive said cam plates and flanges engaged by said side plates.
65. The combination with an oscillatory restricting shaft having an arm, and a wedge system including a wedge bar, of a releasing shaft having an arm, a link pivoted to one of said arms and having a stud and slot connection with the other of said arms, and means operated by said link for controlling said wedge bar.
66. The combination with an oscillatory restricting shaft having an arm and a wedge system including a wedge bar, of a releasing shaft having an arm, a link pivoted to the arm on said restricting shaft and having a stud and slot connection with the arm on said releasing shaft, and means operated by said link for controlling said wedge bar.
67. The combination with an oscillatory restricting shaft having an arm and a wedge system including a wedge bar, of a dog pivoted to said wedge bar by a fixed pivot, said dog being movable on said pivot into and out of operative position, means adapted to engage said dog when in operative position and move said wedge bar, and means connecting said dog with the arm on said restricting shaft.
68. The combination with an oscillatory restricting shaft having an arm and a wedge system including a wedge bar, of a releasing shaft having an arm, a link pivoted to one of said arms and having a stud and slot connection with the other of said arms, a dog pivoted to said wedge bar by a fixed pivot and operatively connected with said link, said dog being movable on said pivot by said link into and out of operative position, and means adapted to engage said dog when in operative position and move said wedge bar.
69. The combination with an oscillatory restricting shaft having an arm and a wedge system including a wedge bar, of a link connected to said arm, and means having a stud and slot connection with said link and operated thereby for controlling said wedge bar.
70. The combination with an oscillatory restricting shaft having an arm and a wedge system including a wedge bar, of a releasing shaft having an arm, a link pivoted to one

of said arms and having a stud and slot connection with the other of said arms, and means having a stud and slot connection with said link and operated thereby for controlling said wedge bar.

71. The combination with an oscillatory restricting shaft having an arm and a wedge system including a wedge bar, of a releasing shaft having an arm, a link pivoted to one

10 of said arms and having a stud and slot connection with the other of said arms, a dog pivoted to said wedge bar by a fixed pivot and having a stud and slot connection with said link, said dog being movable on said

15 pivot by said link into and out of operative position, and means adapted to engage said dog when in operative position and move said wedge bar.

72. The combination with voting members 20 and party levers, of locking mechanism for the voting members, a wedge system for locking the party levers including a wedge bar, a restricting shaft having an arm, a releasing shaft having an arm loosely connected with said wedge bar, a link pivoted to one of said arms and having a stud and slot connection with the other of said arms, means operated by said link for controlling said wedge bar, and means whereby said 30 first named locking mechanism is operated by said wedge bar.

73. The combination with voting members and party levers, of a two part restricting shaft, mechanism for locking the voting 35 members connected with one part of said shaft, and mechanism for locking the party levers connected with the other part of said shaft.

74. The combination with voting mechanism, of a two part restricting shaft, mechanism connected with each part of said shaft for locking a portion of the voting mechanism, and means for detachably connecting the parts of said shaft.

40 75. The combination with voting members and party bars, of a two part restricting shaft, mechanism for locking the voting members connected with one part of said shaft, mechanism for locking the party levers connected with the other part of said shaft, and means for detachably connecting said parts.

76. The combination with voting mechanism, of a two part restricting shaft, mechanism connected with each part of said shaft for locking a portion of the voting mechanism, and a sleeve for detachably connecting said parts.

77. The combination with voting mechanism, of a two part restricting shaft, the ends of said parts being slotted, mechanism connected with each of said parts for locking a portion of the voting mechanism, and a sleeve inclosing said ends and having pins 60 engaged in said slots.

78. The combination with voting mechanism, of a two part restricting shaft, the ends of said parts being separated and being provided with slots, a sleeve connecting said parts and slidably mounted thereon, pins carried by said sleeve and adapted to engage said slots, and mechanism connected with each of said parts for locking a portion of the voting mechanism.

79. The combination with voting mechanism, of a two part restricting shaft, means for detachably connecting said parts, means for locking said connecting means in connecting position, and mechanism connected with each of said parts for locking a portion 80 of the voting mechanism.

80. The combination with voting mechanism, of a two part restricting shaft, means for detachably connecting said parts, means for locking said connecting means in connecting position, said locking means being adapted to release said connecting means when said restricting shaft is in a certain angular position, and mechanism connected with each of said parts for locking a portion 90 of the voting mechanism.

81. The combination with voting mechanism, of a two part restricting shaft, a sleeve connecting the ends of said parts and movable longitudinally thereof to disconnect the 95 same, means to hold said sleeve against longitudinal movement, and mechanism connected with each of said parts for locking a portion of the voting mechanism.

82. The combination with voting mechanism, of two part restricting shaft, a sleeve connecting the ends of said parts and movable longitudinally thereof to disconnect the same, a flange engaging the end of said sleeve to hold the same against longitudinal 105 movement, and mechanism connected with each of said parts for locking a portion of the voting mechanism.

83. The combination with voting mechanism, of a two part restricting shaft, mechanism connected with each part of said shaft for locking a portion of the voting mechanism, a sleeve connecting said parts, and a bearing for said sleeve.

84. The combination with voting mechanism, of a two part restricting shaft, mechanism connected with each part of said shaft for locking a portion of the voting mechanism, means for detachably connecting said parts, and means for locking one of said 115 parts against rotation when disconnected.

85. The combination with voting mechanism, of a two part restricting shaft, mechanism connected with each part of said shaft for locking a portion of the voting mechanism, means for detachably connecting said parts, and means for locking said connecting means in connecting position, said locking means being adapted to release said connecting means when said shaft is in a certain 120 125 130

angular position to permit said parts to be disconnected and thereafter to lock one of said parts against rotation.

86. The combination with voting mechanism, of a two part restricting shaft, mechanism connected with each part of said shaft for locking a portion of the voting mechanism, a sleeve permanently connected with one of said parts and movable into and out of connecting engagement with the other of said parts, and means for locking said sleeve against rotation when moved out of connecting engagement with said other part.

87. The combination with voting mechanism, of a two part restricting shaft, mechanism connected with each part of said shaft for locking a portion of the voting mechanism, a sleeve permanently connected with one of said parts and movable longitudinally of said shaft into and out of connecting engagement with the other of said parts, and means to hold said sleeve against longitudinal movement except when said sleeve is in a certain angular position and to lock said sleeve against rotation when said sleeve is moved out of connecting engagement with said other part.

88. The combination with voting mechanism, of a two part restricting shaft, mechanism connected with each part of said shaft for locking a portion of the voting mechanism, a sleeve permanently connected with one of said parts and movable longitudinally of said shaft into and out of connecting engagement with the other of said parts, said sleeve having a flattened portion, and a flange adapted to engage said flattened portion and lock said sleeve against rotation when said sleeve is moved out of connecting engagement with said other part.

89. The combination with voting mechanism, of a two part restricting shaft, mechanism connected with each part of said shaft for locking a portion of the voting mechanism, a sleeve permanently connected with one of said parts and movable longitudinally of said shaft into and out of connecting engagement with the other of said parts, said sleeve having a flattened portion, and a flange engaging the end of said sleeve to hold the same against longitudinal movement except when opposite said flattened portion and adapted to engage said flattened portion and lock said sleeve against rotation when said sleeve is moved out of connecting engagement with said other part.

90. The combination with voting mechanism, of a two part restricting shaft, mechanism connected with each part of said shaft for locking a portion of the voting mechanism, and means for detachably connecting the parts of said shaft, said means being movable to connect said parts only when said parts are in a certain relative angular position.

91. The combination with voting mechanism, of a two part restricting shaft, mechanism connected with each part of said shaft for locking a portion of the voting mechanism, means for detachably connecting the parts of said shaft, said means being movable to connect said parts only when said parts are in a certain relative angular position, and means for locking one of said parts against rotation when disconnected. 75

92. The combination with voting mechanism, of a two part restricting shaft, mechanism connected with each part of said shaft for locking a portion of the voting mechanism, means for detachably connecting the parts of said shaft, said means being movable to connect said parts only when said parts are in a certain relative angular position, and means for locking one of said parts against rotation when disconnected and for preventing disconnection of the parts except when said last named part is in a certain angular position. 85

93. The combination with voting members and independent voting mechanism, of mechanism for resetting said voting members, and means operated by a part of said independent voting mechanism for locking said resetting mechanism when said independent voting mechanism is operated. 95

94. The combination with voting members, party levers, and independent voting mechanism, of mechanism for resetting said voting members and party levers, and means operated by a part of said independent voting mechanism for locking said resetting mechanism when said independent voting mechanism is operated. 100

95. The combination with voting members and independent voting mechanism including a clutch controlling bar, of mechanism for resetting said voting members, and means carried by said clutch controlling bar for locking said resetting mechanism when said bar is operated. 105

96. The combination with voting members and independent voting mechanism, of mechanism for resetting said voting members including an operating bar, and means operated by a part of said independent voting mechanism for engaging said bar to lock said resetting mechanism when said independent voting mechanism is operated. 115

97. The combination with voting members and independent voting mechanism including a clutch controlling bar, of mechanism for resetting said voting members including an operating bar, and means carried by said clutch controlling bar for engaging said operating bar to lock said resetting mechanism when said clutch controlling bar is operated. 120

98. The combination with voting members and independent voting mechanism including a clutch controlling bar, of mecha- 130

nism for resetting said voting members including an operating bar having an extension provided with a hook, and a catch plate carried by said clutch controlling bar and arranged to engage said hook and lock said operating bar when said clutch controlling bar is operated.

99. The combination with voting members and independent voting mechanism, of 10 a resetting shaft, an arm on said shaft, an operating bar directly connected with said arm, connections between said operating bar and the voting members, actuation of the resetting shaft acting to reset all operated 15 voting members, and means operated by a part of said independent voting mechanism for engaging said bar to lock the same when said independent voting mechanism is operated.

100. The combination with voting members, party levers, and mechanism for locking the party levers, of resetting mechanism for unlocking the party levers, and means for locking said resetting mechanism.

101. The combination with voting members, interlocking mechanism for said voting members, party levers, and mechanism for locking the party levers, of resetting mechanism for unlocking the party levers, and 30 means for locking said resetting mechanism.

102. The combination with voting members, party levers, and means for resetting said voting members and party levers after the voting operation, of mechanism for locking the party levers, auxiliary resetting mechanism for unlocking the party levers, and means for locking said last-named resetting mechanism.

103. The combination with voting members, party levers, and mechanism for locking the party levers, of resetting mechanism for unlocking the party levers including an operating bar, and a manually operated latch for engaging the end of said bar to lock said resetting mechanism.

104. The combination with voting members, party levers, and mechanism for locking the party levers, of a resetting shaft, an arm on said shaft, an operating bar directly 50 connected with said arm, connections between said operating bar and said locking mechanism, actuation of the resetting shaft acting to unlock the party levers, and means for locking said operating bar.

105. The combination with voting mechanism, counter grid operating shafts, and a main operating shaft operatively connected with said voting mechanism, of a main operating bar operatively connected with said counter grid operating shafts, and means for detachably connecting said bar with said main operating shaft.

106. The combination with voting mechanism and a main operating shaft opera-

tively connected with said mechanism, of a 65 main operating bar, an arm on said shaft, a link pivoted to said arm, and a plate on said main operating bar, said link and plate being provided with apertures for the reception of a detachable connecting pin. 70

107. The combination with voting mechanism and a main operating shaft operatively connected with said mechanism, of a main operating bar, an arm on said shaft, a link pivoted to said arm, a plate on said 75 main operating bar, said link and plate being provided with apertures for the reception of a connecting pin, and a latch for retaining said pin in place.

108. The combination with voting mechanism, a main operating shaft operatively connected therewith, and counter grid operating shafts, of a main operating bar connected with said main operating shaft and detachably connected with said counter grid 85 operating shafts.

109. The combination with voting mechanism, a main operating shaft operatively connected therewith, and counter grid operating shafts provided with pinions, of a 90 main operating bar connected with said main operating shaft and provided with racks engaging said pinions, said bar being movable to carry said racks into and out of engagement with said pinions. 95

110. The combination with voting mechanism, a main operating shaft operatively connected therewith, and counter grid operating shafts, of a main operating bar connected with said main operating shaft and detachably connected with said counter grid operating shafts, and positioning means for preventing said main operating bar and counter grid operating shafts from being connected except in a certain relative position. 100

111. The combination with voting mechanism, a main operating shaft operatively connected therewith, and counter grid operating shafts, of a main operating bar connected with said main operating shaft, said counter grid operating shafts and bar being movable into and out of operative engagement, a hub on one of said counter grid operating shafts provided with a recess, and 115 a pin projecting from said bar and adapted to enter said recess.

112. The combination with voting mechanism, a main operating shaft operatively connected therewith, and counter grid operating shafts provided with pinions, of a main operating bar connected with said main operating shaft and provided with racks engaging said pinions, said bar being movable to carry said racks into and out of engagement with said pinions, and positioning means for preventing said racks from being moved into engagement with said pin- 120 125

ions except when said pinions are in a certain position.

113. The combination with voting mechanism, counter grid operating shafts, and a main operating shaft operatively connected with said voting mechanism, of a main operating bar detachably connected with said counter grid operating shafts, and means for detachably connecting said bar with said main operating shaft.

114. The combination with voting mechanism, counter grid operating shafts, and a main operating shaft operatively connected with said voting mechanism, of a main operating bar detachably connected with said counter grid operating shafts, an arm on said main operating shaft, a link pivoted to said arm, and a plate on said main operating bar, said link and plate being provided with apertures for the reception of a connecting pin.

115. The combination with voting mechanism, counter grid operating shafts provided with pinions, and a main operating shaft operatively connected with said voting mechanism, of a main operating bar provided with racks engaging said pinions, said bar being movable to carry said racks into and out of engagement with said pinions, and means for detachably connecting said bar with said main operating shaft.

116. The combination with voting mechanism, counter grid operating shafts provided with pinions, and a main operating shaft operatively connected with said voting mechanism, of a main operating bar provided with racks engaging said pinions, said bar being movable to carry said racks into and out of engagement with said pinions, an arm on said main operating shaft, a link pivoted to said arm, and a plate on said main operating bar, said link and plate being provided with apertures for the reception of a connecting pin.

117. The combination with voting mechanism, a main operating shaft operatively connected therewith, and counter grid operating shafts, of a main operating bar detachably connected with said counter grid operating shafts, positioning means for preventing said parts from being connected except in a certain relative position, and means for detachably connecting said bar with said main operating shaft.

118. The combination with voting mechanism, a main operating shaft operatively connected therewith and counter grid operating shafts, of a main operating bar detachably connected with said counter grid operating shafts, an arm on said main operating shaft, a link pivoted to said arm, a plate on said main operating bar, said link and plate being provided with apertures for the reception of a connecting pin, and

positioning means for preventing said main operating bar and counter grid operating shafts from being connected except in a certain relative position.

119. In a voting machine, in combination, a paper feed shaft, a counter grid operating shaft, and means for normally positively connecting said shafts but movable to disconnect the same.

120. The combination with voting mechanism and a main operating shaft operatively connected therewith, of a paper feed shaft, a counter grid operating shaft, means for detachably connecting said paper feed shaft and counter grid operating shaft, and a main operating bar operatively connected with said main operating shaft and detachably connected with said counter grid operating shaft.

121. The combination with voting mechanism and a main operating shaft operatively connected therewith, of a paper feed shaft, a counter grid operating shaft, means for detachably connecting said paper feed shaft and counter grid operating shaft, a main operating bar detachably connected with said main operating shaft and with said counter grid operating shaft, and positioning means for preventing said main operating bar and counter grid operating shaft from being connected except in a certain relative position.

122. The combination with voting mechanism and a main operating shaft operatively connected therewith, of a paper feed shaft, a counter grid operating shaft, means for detachably connecting said paper feed shaft and counter grid operating shaft, a main operating bar detachably connected with said counter grid operating shaft, and means for detachably connecting said bar with said main operating shaft.

123. In a voting machine, the combination of a paper feed shaft, a gear on said shaft, a counter grid operating shaft having a gear meshing with said first named gear, one of said gears being loosely mounted on the corresponding shaft, and a clutch for connecting said gear with its shaft.

124. In a voting machine, the combination of a paper feed shaft, a gear fast on said shaft, a counter grid operating shaft having an eccentric fast thereto and a pinion loosely mounted thereon, said pinion meshing with said gear, and means for detachably connecting said pinion with said eccentric.

125. In a voting machine, the combination of a paper feed shaft, a counter grid operating shaft, means for detachably connecting said shafts, and means for preventing said shafts from being disconnected except in a certain relative position.

126. The combination with voting mech-

anism and a main operating shaft operatively connected therewith, of a paper feed shaft, a counter grid operating shaft, means for detachably connecting said last named shafts, means for preventing said shafts from being disconnected except in a certain relative position, a main operating bar detachably connected with said main operating shaft and with said counter grid operating shaft, and positioning means for preventing said main operating bar and counter grid operating shaft from being connected except in a certain relative position.

127. In a voting machine, the combination of a paper feed shaft, a gear fast to said shaft and provided with a flange having a portion cut away, a counter grid operating shaft, a gear loose on said shaft and meshing with the gear on said paper feed shaft, a clutch for connecting said loose gear to its shaft, and a member for controlling said clutch, said member having a projection engaging said flange.

128. The combination with voting mechanism, a main operating bar, and a main operating shaft operatively connected with said voting mechanism and with said bar, of a counter grid operating shaft actuated by said bar, and means independent of said bar for actuating said shaft.

129. The combination with voting mechanism, a main operating bar, and a main operating shaft operatively connected with said voting mechanism and with said bar, of a counter grid operating shaft actuated by said bar, a paper feed shaft, means for detachably connecting said counter grid operating and paper feed shafts, and means independent of said main operating bar for actuating said counter grid operating shaft.

130. The combination with voting mechanism, and a main operating shaft operatively connected therewith, of a counter grid operating shaft, a main operating bar connected with said main operating shaft and detachably connected with said counter grid operating shaft, and means independent of said main operating bar for actuating said counter grid operating shaft.

131. The combination with voting mechanism, and a main operating shaft operatively connected therewith, of a counter grid operating shaft, a main operating bar connected with said main operating shaft and detachably connected with said counter grid operating shaft, a paper feed shaft, means for detachably connecting said counter grid operating and paper feed shafts, and means independent of said main operating bar for actuating said counter grid operating shaft.

132. The combination with voting mechanism, and a main operating shaft operatively connected therewith, of a counter

grid operating shaft, a main operating bar 65 detachably connected with said main operating shaft and with said counter grid operating shaft, and means independent of said main operating bar for actuating said counter grid operating shaft.

133. The combination with voting mechanism and a main operating shaft operatively connected therewith, of a main operating bar, a counter grid operating shaft actuated by said bar, means for detachably connecting said bar with said main operating shaft, and means independent of said bar for actuating said counter grid operating shaft.

134. The combination with voting mechanism and a main operating shaft operatively connected therewith, of a main operating bar, means for detachably connecting said bar with said main operating shaft, a counter grid operating shaft actuated by 85 said bar, a paper feed shaft, means for detachably connecting said counter grid operating and paper feed shafts, and means independent of said main operating bar for actuating said counter grid operating shaft. 90

135. The combination with voting mechanism and a main operating shaft operatively connected therewith, of a counter grid operating shaft, a main operating bar detachably connected with said counter grid 95 operating shaft for actuating the same, means for detachably connecting said bar with said main operating shaft, a paper feed shaft, means for detachably connecting said counter grid operating and paper feed 100 shafts, and means independent of said main operating bar for actuating said counter grid operating shaft.

136. The combination with voting mechanism, a main operating bar, and a main operating shaft operatively connected with said voting mechanism and with said bar, of a counter grid operating shaft actuated by said bar, and a counter setting shaft for actuating said counter grid operating shaft 110 independently of said bar.

137. The combination with voting mechanism, a main operating bar, and a main operating shaft operatively connected with said voting mechanism and with said bar, of a pair of counter grid operating shafts actuated by said bar, and a counter setting shaft geared to said counter grid operating shafts.

138. The combination with voting mechanism and a main operating shaft operatively connected therewith, of a pair of counter grid operating shafts, a main operating bar detachably connected with said main operating shaft and with said counter 120 grid operating shafts, a counter setting shaft connecting said counter grid operating shafts and permanently engaged there-

- with, and positioning means associated with one of said counter grid operating shafts for preventing said shaft and said main operating bar from being connected except in a certain relative position. 5
139. The combination with a casing, voting mechanism, a main operating bar, and a main operating shaft operatively connected with said voting mechanism and with said bar, of a counter grid operating shaft actuated by said bar, and a counter setting shaft for actuating said counter grid operating shaft independently of said bar, said counter setting shaft being provided without the casing with means for the attachment of a crank or wrench. 10
140. The combination with voting mechanism, a main operating bar, and a main operating shaft operatively connected with said voting mechanism and with said bar, of a counter grid operating shaft actuated by said bar, and a counter setting shaft for actuating said counter grid operating shaft independently of said bar, said counter setting shaft being connected with said counter grid operating shaft by spiral gears. 15
141. The combination with voting mechanism including lines of voting members, party levers, mechanism for locking said voting members, and mechanism for releasing all of said voting members and locking all of said party levers, of primary locking mechanism including means for locking the voting members in any line or lines. 20
142. The combination with lines of voting members, party levers, a two part restricting shaft, mechanism for locking the voting members connected with one part of said shaft, and mechanism for locking the party levers connected with the other part of said shaft, of primary locking mechanism including means for locking the voting members in any line or lines. 25
143. The combination with lines of voting members, members actuated by any voting member in a line, party levers, a two part restricting shaft, mechanism for locking the voting members connected with one part of said shaft, and mechanism for locking the party levers connected with the other part of said shaft, of primary locking mechanism including bolts movable into and out of a position to engage said members actuated by the voting members to lock the corresponding lines of voting members. 30
144. The combination with lines of voting members, party levers, a two part restricting shaft, mechanism for locking the voting members connected with one part of said shaft, mechanism for locking the party levers connected with the other part of said shaft, means for detachably connecting said parts, and means for locking said part connected with the party lever locking mechanism in locking position when disconnected, of primary locking mechanism including means for locking the voting members in any line or lines. 35
145. The combination with lines of voting members, party levers, mechanism for locking the party levers, resetting mechanism for unlocking the party levers, and means for locking said resetting mechanism, of primary locking mechanism including means for locking the voting members in any line or lines. 40
146. The combination with party bars, party levers, resetting bars having studs, a wedge system for locking the party levers including wedge plates having openings to receive said studs, of primary locking mechanism including bolts movable into and out of a position to engage said studs. 45
147. The combination with voting members, party levers and connections between the party levers and voting members, of locking mechanism for the voting members, locking mechanism for the party levers, and means carried by said last named locking mechanism for engaging and operating said first named locking mechanism. 50
148. The combination with voting members, party levers and connections between the party levers and voting members, of locking mechanism for the voting members including a locking bar, locking mechanism for the party levers including a wedge bar, and means carried by said wedge bar for engaging and operating said locking bar. 55
149. The combination with voting mechanism, of a two part restricting shaft, mechanism connected with each part of said shaft for locking a portion of the voting mechanism, a sleeve connecting the ends of said parts and movable longitudinally thereof to disconnect the same, and a plate provided with a bearing for said sleeve and with a flange engaging the end of said sleeve to hold the same against longitudinal movement. 60
150. The combination with voting members arranged in party lines and office columns and party levers operatively connected with the voting members in the several party lines, of a two part restricting shaft, mechanism for locking the party levers connected with one part of said shaft, and mechanism connected with the other part of said shaft for locking the voting members in certain office columns. 65
151. The combination with voting members arranged in party lines and office columns and party levers operatively connected with the voting members in the several party lines, of a two part restricting shaft, mechanism for locking the party levers connected with one part of said shaft, mechanism connected with the other part of said shaft for 70

locking the voting members in certain office columns, and means for detachably connecting the parts of said shaft.

152. The combination with voting members arranged in party lines and office columns and party levers operatively connected with the voting members in the several party lines, of a two part restricting shaft, mechanism for locking the party levers connected with one part of said shaft, mechanism connected with the other part of said shaft for locking the voting members in certain office columns, and a sleeve for detachably connecting said parts.

153. The combination with voting members arranged in party lines and office columns and party levers operatively connected with the voting members in the several party lines, of a two part restricting shaft, mechanism for locking the party levers connected with one part of said shaft, mechanism connected with the other part of said shaft for locking the voting members in certain office columns, means for detachably connecting the parts of said shaft, and means for locking said connecting means in connecting position.

154. The combination with voting members arranged in party lines and office columns and party levers operatively connected with the voting members in the several party lines, of a two part restricting shaft, mechanism for locking the party levers connected with one part of said shaft, mechanism connected with the other part of said shaft for locking the voting members in certain office columns, means for detachably connecting the parts of said shaft, and means for locking one of said parts against rotation when disconnected.

155. The combination with voting members arranged in party lines and office columns and party levers operatively connected with the voting members in the several party lines, of a two part restricting shaft, mechanism for locking the party levers connected with one part of said shaft, mechanism connected with the other part of said shaft for locking the voting members in certain office columns, means for detachably connecting the parts of said shaft, and means for locking the part of said shaft which is connected with said party lever locking mechanism against rotation when disconnected.

156. The combination with voting members arranged in party lines and office columns and party levers operatively connected with the voting members in the several party

lines, of a two part restricting shaft, mechanism for locking the party levers connected with one part of said shaft, mechanism connected with the other part of said shaft for locking the voting members in certain office columns, a sleeve permanently connected with one of said parts and movable into and out of connecting engagement with the other of said parts, and means for locking said sleeve against rotation when moved out of connecting engagement with said other part.

157. The combination with voting members arranged in party lines and office columns and party levers operatively connected with the voting members in the several party lines, of a two part restricting shaft, mechanism for locking the party levers connected with one part of said shaft, mechanism connected with the other part of said shaft for locking the voting members in certain office columns, means for detachably connecting said parts, and means for locking said connecting means in connecting position, said locking means being adapted to release said connecting means when said shaft is in a certain angular position to permit said parts to be disconnected and thereafter to lock one of said parts against rotation.

158. The combination with lines of voting members, members actuated by any voting member in a line, catches for locking the voting members in the several lines, and a locking bar by which said catches are released, of means carried by the members which are actuated by the voting members for engaging and operating said locking bar, and auxiliary releasing mechanism having means for engaging and operating said bar.

159. The combination with lines of voting members, members actuated by any voting member in a line, catches for locking the voting members in the several lines, and a locking bar by which said catches are released, of means carried by the members which are actuated by the voting members for engaging and operating said locking bar, and auxiliary releasing mechanism having means for engaging and operating said bar, the several means for engaging and operating said locking bar being constructed and arranged to hold said bar in unlocking position after said operation.

In testimony whereof I affix my signature in presence of two witnesses.

CHARLES C. ABBOTT.
